CLAIM

The ornamental design for a beverage container for attaching to a person, as shown and described.

DESCRIPTION

FIG. 1 is left side elevation view of a beverage container for attaching to a person showing our design (the right side elevation is a mirror image of the left side view and is therefore omitted);

FIG. 2 is a front elevation view thereof;

FIG. 3 is a rear elevation view thereof;

FIG. 4 is a top plan view thereof; and,

FIG. 5 is a bottom plan view thereof.

The broken line showing of environment in FIGS. 1-5 is for illustrative purposes only and forms no part of the claimed design.
